(57) **CLAIM**

The ornamental design for a trophy putter, as shown and described.

DESCRIPTION

FIG. 1 is a front elevation view of a trophy putter.

FIG. 2 is a rear elevation view of the trophy putter of FIG. 1.

FIG. 3 is an isometric view of the trophy putter of FIG. 1; and,

FIG. 4 is a cross-sectional view of the trophy putter of FIG. 1, taken on the line 4-4 in FIG. 1.

Portions of FIGS. 1 through 4 are shown in broken lines illustrating portions of the article that form no part of the claimed design.

1 Claim, 4 Drawing Sheets

FIG. 1

FIG. 2

FIG. 3

FIG. 4
